UNITED STATES PATENT OFFICE

HARRY LEBERMAN, OF NEW YORK, N. Y., ASSIGNOR TO GROOVE LOCK CO. INC., OF NEW YORK, N. Y., A CORPORATION OF NEW YORK

FASTENING DEVICE

Application filed September 24, 1929. Serial No. 394,813.

This invention relates to fastening devices, the invention being more particularly related to fastening devices of the kind suitable for use in connection with ladies' and misses' handbags, pocketbooks or other articles requiring simple and efficient means whereby to secure two parts or sections of the article together or release the same.

An object of the invention is the provision of an improved fastening device of the character described, and one which will have improved and simplified means for securing the parts of the device together and as well for releasing them.

Another object of the invention is the provision of a fastening device composed of few parts, cheap to manufacture and easy to apply and assemble, and which will, when assembled, possess the characteristics of neatness, strength, durability and symmetry.

Other objects of the invention will appear hereinafter.

The invention consists in the improved fastening device and in the form, construction and arrangement of parts, which will be hereinafter more fully described and subsequently incorporated in the subjoined claims.

For a full understanding of the invention, reference is to be had to the accompanying drawings, which form a material part of this specification, and in which—

Fig. 1 represents a fragmentary front elevational view of an article equipped with my improved fastening device;

Fig. 2 represents a section taken on the line 2—2 of Fig. 1;

Fig. 3 represents a cross section taken on line 3—3 of Fig. 1;

Fig. 4 represents a detailed perspective view of one of the parts of the fastening device, the button member being omitted;

Fig. 5 represents a detailed perspective view of another part of the fastening device; and

Fig. 6 represents an elevation of a modified form of construction in which a stop is provided at each end of the rail.

The preferred form of construction, as

illustrated in the accompanying drawings, comprises a plate 10 placeable over a plate 11, the plate 10 constituting an essential part of the fastening device and being secured to the cover or flap 12 of the article, while the plate 11 constitutes another essential part of the device and is secured to the wall or body portion 13 of the article.

In the illustrative embodiment, the plate 10 is represented as being provided with two concavely curved notches 14 and 15 and with a keeper portion or edge 16 separating the two notches. As herein represented, a plate 17, corresponding in shape and size with the plate 10 is united with the latter by means of a transverse connection 18 which joins the corresponding portions 16 and 19 of the two plates. As best illustrated in Fig. 5, the two plates 10 and 17 are connected in spaced apart parallel relation so as to embrace the opposite sides of the flap or cover 12 which in practice is folded over the body portion or wall 13. The two plates 10 and 17 may be secured to the flap or cover 12 by means of rivet devices 20 or any other means suitable for the purpose.

To one face of the plate 11 are soldered or otherwise secured the prong devices 21 which are taken through the wall or body portion 13 and then bent thereupon as shown in Fig. 2, whereby the plate 11 is secured in place flatwise upon the wall or body portion 13. Said plate 11 is provided lengthwise thereof with a rail 22 of T-shaped form in cross section as will appear from an inspection of Fig. 3. Mounted upon the head of this rail for sliding movement therealong is a button member 23, herein disclosed as including a shell 24 fashioned to produce underneath parts 25 parallel with the face of the plate 11 and flange parts 26 slidably embracing the head of the rail as clearly shown in Fig. 3. Arranged within the shell, as best shown in Fig. 2, is a spring member 27 having an outwardly bowed portion 28 protruding through an opening 29 in the base of the shell, so as to have frictional engagement with the top of the head of the rail. Said spring permits the button member to be slid along the rail and at the same

time affords means for maintaining the button member in the position to which it is moved.

The plate 11 is represented as provided with an outwardly projecting pin 30 receivable in a recess or keyway 31 provided in the plate 17, and these parts are so positioned that when the flap or cover 12 is folded over the wall or body portion 13 with the pin 30 entered in the recess 31, the keeper edge 16 will be parallel with but spaced from the head of the rail, and in this relationship the concave notches 14 and 15 constitute escape openings adjacent the rail. Said concave notches 14 and 15 are of a size to permit the button member to pass therethrough. The rail 22 is provided at one end thereof with a stop 32 for the button member; and when the button member is moved into position to abut the stop 32, it can be passed through the concave notch 14 to permit the application or removal of the plate 10. When the plate 10 has been placed over the plate 11 with the recess 31 receiving the pin 30, the button member may be slid along the rail and over the keeper edge 16 whereby to secure the parts together against lateral separation one outwardly from the other.

In the embodiment of the invention illustrated in Fig. 4, the rail is provided with a stop 33 to limit the movement of the button to that position where it will be in proper engagement over the keeper edge 16. In this form of construction, it will be manifest that the button member, being slidable only between the stops 32 and 33 can be passed only through the concave notch 14, the other concave notch 15 being provided in this instance only for the purpose of insuring a well-balanced and symmetrical device. If desired, however, the concave notch 15 may be omitted.

In the modified form of construction shown in Fig. 6 the stop 33 has been eliminated, while the rail is provided with an end stop 34 against which the button member may be moved when it is to be passed through the concave notch 15. In this form of construction, the button member may be moved from the keeper edge against the stop 32 for escape through the concave notch 14, or it may be moved into the opposite direction against the stop 34 for escape through the concave notch 15.

From the foregoing description, taken in connection with the accompanying drawing, it will be seen that I have provided a very simple, practical and efficient fastening device, and one which is composed of few parts, cheap to manufacture, apply and assemble.

It will be manifest that I have disclosed a thoroughly satisfactory form of fastening device which embodies the features of ad-

vantage enumerated in the statement of invention, and while I have, in the present instance, shown and described certain preferred embodiments of the invention as reduced to practice, it is to be understood that the constructions are susceptible of modification in various particulars without departing from the spirit or scope of my invention or sacrificing any of its advantages.

I claim:

1. A fastening device for the purpose set forth, comprising a plate provided with a rail, a second plate adapted to overlie the first plate and provided with a keeper portion and a notch in adjacency, means for preventing flatwise shifting of one plate with respect to the other and a button member on the rail adapted to pass through said notch, said button member being slidable along the rail for engagement with the keeper portion whereby to secure the plates together against lateral separation one outwardly from the other.

2. A fastening device for the purpose set forth, comprising two plates consisting of an outer plate placeable over an inner plate, a rail on the inner plate, a keeper portion and a notch on the outer plate, the keeper portion being parallel to the rail and the notch affording an opening adjacent the rail, means to afford and maintain an engagement between the plates to prevent shifting movement thereof, and a button member which is receivable through said opening slidable along said rail and engageable with said keeper portion whereby to secure the plates together against lateral separation one outwardly from the other.

3. A fastening device for the purpose set forth, comprising two plates placeable one over the other in flatwise relation, the overlying plate having a keeper portion and a notch in adjacency, the other of the plates having a rail opposite said keeper portion and notch, means for preventing flatwise shifting of one plate with respect to the other, a button member which is receivable through said notch slidable along said rail and engageable with said keeper portion to secure the plates together against lateral separation one outwardly from the other, and stop means for said button member.

4. A fastening device for the purpose set forth, comprising two plates placeable one over the other in flatwise relation, the overlying plate having a keeper portion and a notch in adjacency, the other of the plates having a rail opposite said keeper portion and notch, a pin on one plate engageable in a guide in the other plate to determine the relative positions of the plates and prevent flatwise shifting movement thereof, a button member carried by the rail and receivable through said notch means, said button member being slidable along the rail.

and engageable with said keeper portion to secure the plates together against lateral separation one outwardly from the other, and stop means for said button member.

5 5. A fastening device for the purpose set forth, comprising two plates consisting of an outer plate placeable over an inner plate, a rail on the inner plate, a keeper portion and two notches on the outer plate, the keeper portion being between the notches and being opposite the rail and the notches affording separate openings adjacent the rail, means for preventing flatwise shifting of one plate with respect to the other, and a button member slidable along the rail and enterable through either of said notches for engagement with said keeper portion whereby to secure the plates together against lateral separation one outwardly from the other.

6. A fastening device for the purpose set forth, comprising a main plate, an overlapping plate contacting flatwise therewith and provided with a free edge portion, a button slidable along the main plate to locking position and along a line parallel to the free edge portion of the overlapping plate, said button having a projecting portion forming between it and the face of the main plate an open space adapted to receive the free edge portion of the overlapping plate, a pin extending from the contacting face of one of said plates, the contacting face of the other plate being provided with a recess to receive said pin, said pin and recess, when engaged, coacting to prevent flatwise shifting of the plates and situated so as to locate said free edge portion adjacent the path of movement of said button and at a point to be received in said open space and to be engaged under said projecting portion on movement of the button to locking position, whereby to maintain the overlapping plate in place with the pin engaging said recess.

45 7. A fastening device for the purpose set forth, comprising a first plate, a second plate placeable flatwise on the first plate and having a free edge portion, a projection on the contacting face of one of the plates engaging a recess in the contacting face of the other plate for preventing flatwise shifting of the plates, a rail on the first plate extending along a line parallel to and into a position in front of said free edge portion 50 when the plates are engaged to prevent flatwise shifting thereof, and a button slidable along the rail and having a lateral part for engaging over the outer face of said free edge portion whereby to secure the plates together against lateral separation one outwardly from the other.

In testimony that I claim the foregoing as my invention, I have signed my name hereto.

65 HARRY LEBERMAN.
